Primary Examiner — April Rivas

(57) **CLAIM**

The ornamental design for a foldable bag, as shown and described.

DESCRIPTION

FIG. 1 is a perspective view of a foldable bag showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a perspective interior view of the foldable bag, in an open configuration thereof;

FIG. 9 is a perspective exterior view of the foldable bag, in an open configuration thereof; and,

FIG. 10 is a perspective exterior view of the foldable bag, with the left and right side open thereof.

The broken lines shown in the drawings depict portions of the foldable bag in which the design is embodied that form no part of the claimed design.
